UNITED STATES PATENT OFFICE.

ROBERT S. JAMES, OF SEATTLE, WASHINGTON.

AUTOMOBILE-CLOCK.

1,158,502.

Specification of Letters Patent.

Patented Nov. 2, 1915.

Application filed December 26, 1914. Serial No. 879,194.

To all whom it may concern:

Be it known that I, ROBERT S. JAMES, a citizen of the United States of America, and a resident of Seattle, in the county of King, in the State of Washington, have invented a new and useful Improvement in Automobile-Clocks, of which the following is a specification.

This invention relates to improvements in automobile clocks provided with an alarm attachment and having an electric switch operated thereby and by the use of which the lighting of the lights at a predetermined time on any automobile equipped with an electric lighting system may be automatically accomplished.

The object of the invention is to provide mechanical means for lighting the necessary lights on an automobile at a certain time in order to comply with traffic regulations, and which device will operate automatically in the absence of the driver. This result is accomplished by providing the clock with terminal wires and connecting them with the wiring system of the automobile to which the device is applied. The alarm attachment is then set in the usual manner for any specific time, the release of the alarm spring resulting in the closing of the circuit and the lighting of the lights. It is optional what particular lights are lighted, the wire connections determining this, the connections being so arranged as to result in the lighting of all the lights, front side and tail, or the side and tail lights alone.

This clock is designed to perform the double function of a time piece for the driver as well as an automatic lighting switch.

With this and other objects in view, the invention resides in certain novel features of construction and combination, and arrangement of parts hereinafter described and claimed.

In the accompanying drawings: Figure 1 represents a rear elevation of an alarm clock to which this invention is applied with the back plate removed; Fig. 2 is a vertical section of the attachment detached; Fig. 3 is an enlarged detail side elevation of the switch lever partly in section; Fig. 4 is a similar view of the means for throwing the switch lever in neutral position; Fig. 5 is a similar view of one of the members carrying one of the electric contacts in a socket to receive a plug.

In the embodiment illustrated, a case or

cabinet C is shown sufficiently large to receive an ordinary sized alarm clock c positioned so that its face may be exposed to view. Mounted in the case C is the device 60 constituting this invention and which comprises a ratchet wheel 1 fixed to the arbor 2 of the main alarm spring and which revolves with said arbor, traveling from right to left on the unwinding of the spring. To 65 the rear of the ratchet wheel 1 loosely mounted on the arbor 2 is a contact switch lever 3 here shown provided with a circular central portion 4 having arms 5 and 6 extending from its periphery at diametrically opposite points, said arms being provided at their terminals with insulating material shown at 7 and having electric contacts 8 mounted therein. These contacts 8 are connected by insulated copper wire 9 which 70 passes over the contact switch lever, thereby avoiding electrification of the parts of the clock. The contact switch lever 3 and the ratchet wheel 1 are preferably constructed of brass. A spring pressed pawl 10 is 75 mounted on one face of the circular portion 4 of the lever 3 with its free end positioned for engagement with the teeth of the ratchet wheel 1, so that when said ratchet wheel is turned from right to left on the turning of 80 the arbor 2, it will be connected with the lever 3 through said pawl 10 and consequently said lever will be correspondingly turned until the contacts 8 carried by the opposite ends thereof engage coöperating 85 contacts 11 carried by the depending arms 12 which are supported in any suitable manner by the casing C. These contacts 11 are connected by suitable wires 13 which 90 extend through the arms 12, with contact points 14 disposed in sockets 15 in the upper ends of the arms 12. Terminal plugs 16 and 16' are mounted in the sockets 15 and are connected respectively by wires 17 and 18 with the leading in and return wires of 95 the car wiring system (not shown). When the terminal plug 16' is inserted in the socket 15 and engaged with the contact 14 therein, a complete circuit is formed through 100 said plugs 16 and 16', and permits the application of the usual car lighting control without relation to the clock contact switch.

A rod 19 is fixed at one end to the arm 6 of the lever 3 and projects upwardly into an insulated member 20 connected with the 105 clock casing and depending therefrom, and which has a bore 21 extending longitudinally

therethrough with an annular shoulder 22 formed intermediately of its ends and which is designed for a purpose soon to be described. The free end of the rod 19 extends 5 into the lower end of the bore 21 and has a pin 19' operating in oppositely disposed slots 20' formed in the side walls of the bore 20 and which serves to limit the movement of rod 19 to prevent its dropping out of the 10 bore. Another rod 23, extends into the upper portion of said bore with its upper end projecting beyond the member 20 and is provided with an actuating handle 24. A coiled spring 25 encircles the rod 23, having 15 one end abutting the shoulder 22 of the bore 21, and its other end secured to the rod 23, so that when said rod 23 is depressed to bring its lower end into engagement with the upper end of the rod 19, the spring 25 20 will operate to return said rod 23 to projected position when it is released. This rod 23 is designed for engaging the rod 19 and depressing said rod 19, thereby moving the arm 6 of the lever 3 downward and the arm 25 5 thereof upward, thus moving the contacts 8 carried by said arms out of engagement with the contacts 11, and thereby breaking the circuit, said lever being then placed in what is termed neutral position where it 30 will remain until again turned by the alarm spring of the clock *c* through the turning of the arbor 2, ratchet wheel 1, and circular member 3, whereby said lever is actuated to bring the contacts carried by the arms thereof 35 5 into electrical engagement with the contacts 11 for closing the circuit and lighting the lights.

I am aware that prior to this invention 40 clocks have been made with alarm attachments operated in conjunction with electric devices, therefore I do not claim such a combination broadly.

I claim as my invention:—

1. The combination with an alarm clock 45 provided with an arbor, of a ratchet wheel fixed to said arbor, a switch lever fulcrumed to turn loosely on said arbor, a pawl carried by said lever and engaging said ratchet wheel, electrical contacts carried by said lever, coöperating contacts connected with an electric source and mounted in the path of the contacts on said lever, said arbor being rotated on the releasing of the alarm whereby said lever is turned to close the circuit, and means under the control of the operator for actuating said lever to break the 50 55 circuit.

2. The combination with an alarm clock having an arbor, of a ratchet wheel fixed 60 to said arbor, a switch lever fulcrumed to turn loosely on said arbor, a pawl carried by said lever and engaging said ratchet

wheel, electrical contacts carried by said lever, coöperating contacts connected with an electric source and mounted in the path 65 of the contacts on said lever, said arbor being rotated on the releasing of the alarm whereby said lever is turned to close the circuit, means under the control of the operator for actuating said lever to break the 70 circuit, and means for holding said lever in neutral position.

3. The combination with electric contacts, a lever fulcrumed intermediately of its ends and having contacts positioned on the ends 75 for engagement with said first mentioned contacts at predetermined intervals, automatically operated means for actuating said lever at a predetermined time to close said circuit, a rod connected with said lever at one side of its fulcrum, and spring projected means for engaging said rod at the will 80 of the operator to actuate said lever to break the circuit.

4. A switch lever comprising a circular 85 central portion having arms extending from its periphery at diametrically opposite points and provided with contacts, a wire connecting said contacts, said circular member having a central aperture therein adapted to be 90 loosely engaged with the arbor of an alarm clock, a ratchet wheel, a pawl carried by said circular member and engaging the teeth of said ratchet wheel, insulating members having contacts disposed in the path of the 95 contacts carried by said lever, means for connecting said contacts with the opposite poles of a source of electricity, said lever being actuated on the rotation of the clock arbor to bring the contacts carried thereby 100 into engagement with the contacts arranged in the path thereof, thereby closing the circuit.

5. The combination with electric contacts 105 connected with the opposite poles of an electric source, a lever fulcrumed intermediately of its ends and having contacts positioned for engagement with said first mentioned contacts at predetermined intervals, automatically operated means for actuating said lever at a predetermined time to close said circuit, a rod extending upwardly from said lever at one side of its fulcrum, a spring 110 pressed rod mounted in the path of said first mentioned rod, and means for depressing said spring pressed rod to bring it into engagement with said first mentioned rod, thereby actuating the lever to throw it into neutral position.
